By Philip A. G. Ferrell 142 Attorney

UNITED STATES PATENT OFFICE.

LEWIS G. COWLES, OF YUTAN, NEBRASKA.

ERASER.

1,408,564.

Specification of Letters Patent.

Patented Mar. 7, 1922.

Application filed July 13, 1920. Serial No. 396,019.

To all whom it may concern:

Be it known that LEWIS G. COWLES, a citizen of the United States, residing at Yutan, in the county of Saunders and State

5 of Nebraska, has invented certain new and useful Improvements in Erasers, of which the following is a specification, reference being had therein to the accompanying drawing.

10 The invention relates to erasers, preferably of the type used for cleaning blackboards and has for its object to provide a device of this character comprising a plurality of T-shaped cleaning elements which are held on 15 an eraser back by means of T-shaped cleats, thereby providing means whereby any of the T-shaped cleaning elements may be renewed as desired, and also providing an eraser which may be easily and quickly constructed, 20 particularly quickly assembled.

A further object is to provide a wire mesh beater for use in connection with the eraser so as to beat and clean the eraser, thereby obviating the common practice of beating 25 together two erasers, which operation obviously does not completely clean the eraser.

With the above and other objects in view the invention resides in the combination and arrangement of parts as hereinafter set 30 forth, shown in the drawings, described and claimed, it being understood that changes in the precise embodiment of the invention may be made within the scope of what is claimed without departing from the spirit of the invention.

35 In the drawings:—

Figure 1 is a perspective view of the eraser. Figure 2 is a longitudinal sectional view taken on line 2—2 of Fig. 1.

40 Figure 3 is a perspective view of one of the cleaning elements.

Figure 4 is a top plan view of the beater.

Figure 5 is a side elevation of the beater.

Referring to the drawings, the numeral 1 45 designates the eraser, and 2 the back thereof. The back is preferably rectangular shaped as shown and has secured thereto, by means of brads 3, T-shaped strips 4, which strips are spaced apart and are adapted to receive 50 therebetween T-shaped cleaning elements 5. The horizontal flanges of the strips 4 overlie the horizontal flanges 6 of the cleaning elements thereby securely holding the cleaning elements against displacement. The cleaning 55 elements 5 located at the ends of the eraser are held in place, not only by the

adjacent T-shaped strips 4, but by the transversely disposed strips 7, the flanges 8 of which overlie the outer flanges 6 of the cleaning elements.

60 It will be seen that any of the cleaning elements which may become worn may be easily removed and replaced by simply removing the retaining strip 4 adjacent the worn cleaning element, and then a new cleaning element may be placed in position and the strip again secured to the back 2. It will also be seen that an eraser is provided which is simple in construction and one which may be cheaply made and quickly 65 assembled.

Referring to the beater the numeral 9 designates a rectangular shaped body formed of wire, having interwoven wire 10 so that when the portion 9 engages the cleaning elements 5 during the beating operation, the dust from the eraser will be allowed to escape to the atmosphere. Extending upwardly from the rear end of the rectangularly shaped body member 9 are brace wires 80 11, which have their ends imbedded as at 12 in a handle member 13, adapted to be grasped by the hand of the operator during a cleaning operation.

The invention having been set forth what 85 is claimed as new and useful is:—

1. A cleaning eraser comprising a rigid body member, said body member having secured to one side thereof a plurality of T-shaped transversely disposed strips in 90 parallel relation to each other and spaced apart, thereby forming transversely disposed T-shaped slots, and a plurality of T-shaped cleaning elements disposed in said T-shaped slots.

95 2. A cleaning eraser comprising a rigid body member, a plurality of T-shaped transversely disposed strips in parallel relation to each other and detachably secured to the rigid body member at equal distances from 100 each other, said T-shaped members having their opposite flanges in horizontal relation to the rigid body member, and their other flange detachably secured to the rigid body member thereby forming T-shaped slots and 105 a plurality of T-shaped cleaning elements disposed in the T-shaped slots and held therein against displacement by the T-shaped strips.

110 In testimony whereof I hereunto affix my signature.

LEWIS G. COWLES,
